(57) **CLAIM**

The ornamental design for a connector, as shown and described.

DESCRIPTION

FIG. 1 is a top and side perspective view of a first embodiment of a connector embodying our new design;

FIG. 2 is a bottom and side perspective view thereof;

FIG. 3 is a top view thereof;

FIG. 4 is a bottom view thereof;

FIG. 5 is a first side view thereof;

FIG. 6 is a second side view thereof;

FIG. 7 is a front view thereof;

FIG. 8 is a back view thereof;

FIG. 9 is another perspective view thereof;

FIG. 10 is a top and side perspective view of a second embodiment of a connector;

FIG. 11 is a bottom and side perspective view thereof;

FIG. 12 is a top view thereof;

FIG. 13 is a bottom view thereof;

FIG. 14 is a first side view thereof;

FIG. 15 is a second side view thereof;

FIG. 16 is a front view thereof; and,

FIG. 17 is a back view thereof.

Broken lines, where shown, are used to illustrate portions of the connector or environmental subject matter that form no part of the claimed design.

As shown in FIGS. 10-16, the dot pattern area on the front portion of the connector represents an area of contrasting appearance only and does not represent any particular color, material, texture or finish.
